UNITED STATES PATENT OFFICE.

LOUIS E. VALCOURT, OF PAWTUCKET, RHODE ISLAND, ASSIGNOR TO LOUIS STERN CO.,
OF PROVIDENCE, RHODE ISLAND, A CORPORATION OF RHODE ISLAND.

WATCH-BRACELET-END HOOK.

Application filed June 16, 1925. Serial No. 37,558.

This invention relates to a watch bracelet end hook; more particularly of the type adapted for attaching the ends of a strap, ribbon, or the like to the bail of a wrist watch; and the object of this invention is to provide simple and practical construction of such a hook to which the end of the strap may be readily releasably attached by a gripping member.

10 A still further object of this invention is to provide a gripping member of such construction that it will engage the end of the hook to prevent its being too readily moved from clamped to released position.

15 A further object of the invention is to so position the gripping member that it restricts or partially closes the mouth of the hook so that the watch bail will be obliged to be snapped both into and out of the hook.

20 With these and other objects in view, the invention consists of certain novel features of construction, as will be more fully described, and particularly pointed out in the appended claims.

25 In the accompanying drawings:

Figure 1 is a side elevation showing a wrist watch and illustrating my improved hook as attaching the ends of a watch bracelet strap thereto.

30 Figure 2 is a perspective view of my improved hook.

Figure 3 is a plan view of the body portion of the hook as cut from sheet stock.

Figure 4 is a perspective view of my gripper member.

35 Figure 5 is a sectional elevation showing my hook with a strap attached thereto.

Figure 6 is a sectional side elevation showing the gripper in released position.

40 It is found in practice desirable to provide a hook for the end of a bracelet strap and the like in which the strap may be releasably secured to the body of the hook by a gripping member, and it is also found desirable to so form the gripper as to provide means for guarding the release of the strap from the gripping member and at the same time so shaping the gripper as to provide a means for preventing inadvertent removal 45 of the hook from the watch bail; and the following is a detailed description of one means by which these advantageous results may be accomplished:—

With reference to the drawings, 10 designates a wrist watch having bail members 11

on either side thereof, and 12 designates the body portion of the attaching hook member which is provided with an extended end 13 folded to provide a hook portion as illustrated in Figure 2, the same being perforated at 14 to permit of greater resiliency and the extremity of the hook being turned slightly outwardly as at 15 to permit the ready entry of the watch bail 11. At the distal end of the body portion of the hook 60 there are provided side ears 16 folded rearwardly from the body and bent inwardly as at 17 to protect the flanges 16 and prevent them from cutting or abrading the wrist of the wearer and at the same time providing a guide for the entry of the strap into the body member. Each of the ears is perforated as at 18 to receive the pivoted trunnions 19 of the gripping member 20 which is formed in substantially L-shape, one arm 70 21 of the L serving as a gripping jaw for binding the strap 22 against the inner face of the body and the other portion or arm 23 of the L-shaped gripper extending inwardly on an incline beneath the end of the hook portion in such position that the end 24 of this arm must be snapped past the end 15 of the hook in moving the gripper to released position.

Further, this arm portion 23 of the gripper being set on an incline, serves as a guide for the entry and also as a guide for the disengagement of the bail 11 to and from the hook portion 13 of the body member, and it will be noticed that the distance between the arm 23 and the hook end 15 is slightly less than the diameter of the bail so that the hook end must be sprung outwardly to permit the bail to be snapped into and out of the hook.

45 It will thus be seen that I have provided a hook which is simple in construction and one which may be adapted to receive various thicknesses of belts which are adapted to be fastened to the body by a gripping member 100 and yet one in which the gripper at the same time also serves to prevent the inadvertent release of the belt and also the inadvertent release of the hook from the bail of a watch.

50 My improved hook is very simple and practical in construction and may be manufactured at the minimum cost and yet is of a strong and durable construction.

55 The foregoing description is directed solely towards the construction illustrated,

but I desire it to be understood that I reserve the privilege of resorting to all the mechanical changes to which the device is susceptible, the invention being defined and 5 limited only by the terms of the appended claims.

I claim:

1. A watch bracelet end hook comprising a body member having a resilient hook-shaped end, a clamping member in said body member for gripping and holding the bracelet strap, said member also serving to restrict the hook opening whereby the watch bail must be snapped into and out of engagement with said hook.

2. A watch bracelet strap end hook comprising a body member having an end portion folded to form a hook, a strap clamp pivoted in said body member, a portion of said clamp also serving to restrict said hook opening and serve as a guide for the exit and entry of the watch bail out of and into the hook.

3. A watch bracelet strap end hook comprising a body member having a resilient hook at one end, a strap clamp pivoted in said body and having a portion extending beneath the end of the hook, said portion

engaging and snapping past the end of said hook in being swung on its pivot to and 30 from release position.

4. A watch bracelet strap hook comprising a body member, an L-shaped strap clamp pivoted in said body member one arm of the clamp being adapted to grip the strap against the body, a hook on the end of the body having its end overlying the other arm of said clamp whereby said other arm must be sprung past the hook end in moving to released position.

5. A watch bracelet strap hook comprising a sheet metal body member having an end portion folded to form a resilient hook, ears folded upon the side of the body at the opposite end thereof, a strap gripping member pivotally mounted in said ears, said gripping member having a portion positioned to restrict the mouth of the hook and having a portion extending beneath said hook end to prevent inadvertent release 50 thereof and to serve as a guide for snapping the bail of the watch into and from said hook.

In testimony whereof I affix my signature.

LOUIS E. VALCOURT.
